The ornamental design for a motor vehicle, toy and/or replica, as shown and described.

DESCRIPTION

FIG. 1 is a front perspective view of a motor vehicle, toy and/or replica;

FIG. 2 is a rear perspective view thereof;

FIG. 3 is a front elevation view thereof;

FIG. 4 is a rear elevation view thereof;

FIG. 5 is a right side perspective view thereof, the left side view being a mirror image thereof; and,

FIG. 6 is a top plan view thereof.

The portions of the motor vehicle, toy and/or replica shown in broken lines are for illustrative and environmental purposes and form no part of the claimed design.
